UNITED STATES PATENT OFFICE.

DAVID WIENER, OF NEW YORK, N. Y.

DOLL.

1,374,343.

Specification of Letters Patent. Patented Apr. 12, 1921.

Application filed December 28, 1918. Serial No. 263,590.

To all whom it may concern:

Be it known that I, DAVID WIENER, a citizen of the United States, residing at New York city, in the county of Bronx, State of New York, have invented certain new and useful Improvements in Dolls; and I do hereby declare the following to be a full, clear, and exact description of the invention, such as will enable others skilled in the art 10 to which it appertains to make and use the same.

This invention relates to dolls, and particularly to the structure of the head and shoulders of dolls of the stuffed or filled 15 type.

Heretofore it has been the practice to provide dolls of this type with heads formed with integral necks adapted to be sewed or otherwise attached to the usual fabric body 20 of the doll. In case of breakage of the head, and this is liable to occur even with the best of the so-called "unbreakable" heads, it is customary to discard the entire doll or to send it away to be repaired, for while new 25 heads are readily obtainable, it is somewhat inconvenient, and also injurious to the body covering of the doll, to remove the old head from the body, particularly if the latter is stuffed with sawdust or similar material. 30 In other words, one usually finds it easier to discard the entire doll and purchase a new one, than to attempt to replace the damaged head.

It is an object of this invention to avoid 35 the loss incident to stuffed dolls of the usual construction, by providing a separate head and shoulder piece suitably connected together so that in case of breakage of the head, it can be quickly and easily replaced 40 without the necessity of removing the shoulder piece from the body. This construction possesses the further advantage over dolls of the usual construction, that a number of different heads may be provided for each 45 body, and since these heads may be easily interchanged, a child can obtain different expressions and other characteristics of the head of its doll, thereby increasing the usefulness of the doll as a source of amusement 50 for the child.

Other advantages of the invention will appear from a detailed description of certain preferred embodiments as illustrated in the accompanying drawings, in which,

55 Figure 1 shows an arrangement provided with one kind of detachable connection and

one mode of attaching the shoulder piece to the body of the doll; Figs. 2 and 3 are elevation and plan views, respectively, of a detachable connection in which the use of screw threads is avoided; Figs. 4 and 5 show other arrangements that may be employed for attaching the heads to the shoulder pieces, and also a modified arrangement for attaching the shoulder piece to the body of the doll; 60 and Figs. 6, 7 and 8 represent in elevation and plan a still further arrangement for detachably connecting a head to a shoulder piece.

In Fig. 1 the shoulder piece 10 is adapted 70 to be sewed to the fabric body 11 as at 12, and the arms 13 may be attached to the sides of the shoulder piece by suitable connecting devices 14. The shoulder piece is provided with an inwardly extending socket 15 which 75 is screw threaded to receive the neck portion 16 of the head 17. With this arrangement it is intended that the shoulder piece shall remain permanently attached to the body of the doll, and there is no possibility 80 of the stuffing falling from the doll even when the head is removed, for the top of the shoulder piece forms a closure for the contents of the body. While one particular head is shown, any number of heads each 85 formed with a screw threaded neck portion may be provided, and these heads can be quickly interchanged as desired.

Figs. 2 and 3 show an arrangement that may be employed in case it is desired to 90 eliminate the use of screw threads in the structure of the head and shoulder piece. In this case the shoulder piece 10' is, as in Fig. 1, sewed to the body of the doll and carries the arms. The top of the shoulder piece is 95 provided with an aperture having outwardly extending radial slots 18 adapted to receive correspondingly shaped lugs 19 projecting from the neck portion 16' of the head. The slots are so disposed with relation to the 100 shoulder piece that when the head is in normal relation to the body, the lugs 19 will occupy substantially the position shown in Fig. 3. In order to hold the head in this position so that it will not be easily turned 105 and disengaged from the shoulder piece, a plate 20 of cardboard, thin metal or similar material may be placed at the top of the shoulder piece and pressed upwardly against the lugs on the neck by the stuffing of 110 the doll.

In Figs. 4 and 5, the shoulder pieces 10"

instead of being sewed to the body of the doll as in the preceding figures, are held in place by carrying the material 11' of the body over the shoulder piece and suitably 5 fastening it to the top of the shoulder piece around the neck of the doll. In Fig. 4, the shoulder piece is provided with a threaded stud 21, onto which the head may be screwed. In Fig. 5 the shoulder piece is 10 formed with an inwardly extending socket 22 provided with a central stud 23 to which the head may be secured, the head being provided with an inwardly threaded socket adapted to fit in the annular recess formed 15 in the shoulder piece.

Figs. 6, 7 and 8 show another arrangement that may be employed for attaching the head to the shoulder piece. In this case the shoulder piece is closed at its top to prevent the 20 leakage of the stuffing, and is additionally provided with an inwardly directed flange 24 of substantially semi-circular contour. The bottom of the neck is provided with an outwardly extending flange 25 adapted to 25 fit under the flange 24. For holding the head in place when inserted, a coöperating flanged movable member 26 of substantially semi-circular contour is provided, and this movable member is connected to the fixed 30 flange 24 by an elastic band 27 located beneath the neck of the doll and adapted to draw the movable member against the fixed member to hold the head in place. With this arrangement it is only necessary to 35 draw member 26 forwardly to permit a head to be removed or replaced, and when the movable member is released it will be drawn against the front of the neck portion to hold the head securely in place.

The embodiments illustrated above are 40 but a few of the many arrangements that may be employed for detachably connecting the head of a doll to a shoulder piece particularly adapted to be attached to the body of a stuffed doll, and it will be understood 45 that various other changes in the details of construction may be made without departing from the principle of the invention.

While the stuffing of the doll has been shown as filling the shoulder piece in some 50 of the figures, it may be kept out of the shoulder piece by a wall 28 of any suitable material, fitted into the bottom of the shoulder piece as shown in Figs. 6 and 7. This arrangement results in a saving of stuffing 55 material and also leaves the shoulder piece empty for the reception of voice-producing or other mechanical arrangements that may be applied to the doll.

60 I claim:

In a stuffed doll, the combination of a 65 stuffed body, a shoulder piece secured thereto, and a head formed separately from the shoulder piece, said shoulder piece being provided with one element of a detachable connection and said head being provided with another element of said connection, said elements coöperating to hold the head rigidly on the shoulder piece so that the head and shoulder piece constitute in effect a single rigid structure, and said elements being 70 readily connectible to permit ready application of the head to the shoulder piece and being readily separable to permit ready detachment of the head from the shoulder 75 piece.

In testimony whereof I affix my signature.
DAVID WIENER.
